Primary Examiner — Robert M Spear*Assistant Examiner* — Kendra L Hamilton(74) *Attorney, Agent, or Firm* — Brinks Gilson & Lione(57) **CLAIM**

We claim the ornamental design for an optical disk, as shown and described.

DESCRIPTION

FIG. 1 is a front perspective view of a first embodiment of an optical disk of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a cross-section view taken along the line 8-8 of FIG. 2;

FIG. 9 is an enlarged view taken along the line 9-9 of FIG. 8; and,

FIG. 10 is an enlarged view of the areas marked as 10 of FIG. 1.

In the drawings, the evenly-spaced broken lines represent unclaimed subject matter and form no part of the claimed design. Additionally, the dash-dot-dash broken lines define the limits of the claimed design.
